The ornamental design for a motorized mobile system key, as shown and described.

DESCRIPTION

FIG. 1 is a side perspective view of a motorized mobile system key mounted on a motorized mobile system showing our new design.

FIG. 2 is a bottom perspective view thereof.

FIG. 3 is a front perspective view thereof.

FIG. 4 is a back top perspective view thereof.

FIG. 5 is a back bottom perspective view thereof.

FIG. 6 is a front view thereof.

FIG. 7 is a back view thereof.

FIG. 8 is a right side view thereof.

FIG. 9 is a left side view thereof.

FIG. 10 is a top view thereof; and,

FIG. 11 is a bottom view thereof.

The broken lines in the Figures show environment or portions of the motorized mobile system key that form no part of the claimed design.

The shade lines in the Figures show contour and do not claim surface ornamentation or treatment.
